UNITED STATES PATENT OFFICE.

EDWARD CAMERON, OF ST. KILDA, VICTORIA, AUSTRALIA.

MILKING-MACHINE.

1,142,488.

Specification of Letters Patent.

Patented June 8, 1915.

Application filed October 2, 1911. Serial No. 652,248.

To all whom it may concern:

Be it known that I, EDWARD CAMERON, a subject of the King of Great Britain, and residing at 13 Fraser street, St. Kilda, State of Victoria, Commonwealth of Australia, have invented new and useful Improvements in Milking-Machines, of which the following is a specification.

This invention relates to a mechanical milker in which the principle of a vacuum or reduced pressure is employed for the purpose of extracting the milk from the cow's teats.

Among the objects which this invention has in view are to avoid the employment of india rubber or the like kind of tubes and to substitute metal or metallic tubes which on account of being more easily and completely cleaned and for other reasons are preferable; to provide means for enabling such metallic tubing to be jointed and used for such purpose; to provide means for mechanically manipulating the cow's udder and adjusting the mechanism to the physical irregularity of the different cows; to provide more effective means for application of the power of the vacuum or reduced pressure (herein termed vacuum) when it has been created in operating the teat cup; to provide means for extracting the milk from the udder by a special downward drawing motion equivalent to or in imitation of the action of the calf sucking and hand milking; to provide a suitable pulsator and a receiving vessel into the latter of which the milk is drawn and from which it is delivered.

One embodiment of the present invention is illustrated in the accompanying drawings partly diagrammatic forming part of the specification in which like characters of reference denote corresponding parts:

Figure 1 is a general diagrammatic view showing the general arrangement of a milking machine constructed according to this invention. Fig. 2 is a perspective view of pulsator. Fig. 3 is a central longitudinal sectional view of pulsator. Figs. 4 and 5 are sectional and side views of the connection between the arm and the milk tube. Figs. 6 and 7 are sectional and side views of the connection between the main air tube and the air tube leading to the claw. Fig. 8 is a view of one of the disk-joints showing the disks, the tube, and the clip fastening. Fig. 9 is an external side view and Fig. 10 a sectional view of the same. Fig. 11 is an elevation of the milk receiver. Fig. 12 is a plan and Fig. 13 a view partly in section of the claw. Fig. 14 is a detail view of the sight tube. Fig. 15 is a vertical section of the teat cup. Fig. 16 is a section on line A—A of Fig. 15. Fig. 17 is a section on line B—B of Fig. 15. Fig. 18 is a section on line C—C of Fig. 15. Fig. 19 is a section on line D—D of Fig. 15.

The present device may be more conveniently described when divided into groups of instrumentalities. These I will describe beginning with the structure whereby the milking device is held in operative position; the second group is formed by the main milk tube and other tubes, cups, and connections which co-act to extract the milk from the udder; the third group is the pulsator and its attachments; the fourth is the receiver and its attachments; and the fifth is the motive power and its transmission. I will refer to these more in detail and somewhat in the stated order.

The structure may be of any convenient form adapted to carry the main milk and air tubes the pulsator the receiver and the vacuum and motive power apparatus. For instance the tubes and parts may be fastened with brackets, hangers and the like to the joists or the posts of the milking shed.

The arm 1 constituting the connection between the means for manipulating the cow's udder and the main milk tube 2, constitutes a novel and valuable feature allowing and enabling india rubber tubes to be dispensed with. The arm is comprised of metallic tubing with certain attachments thereto.

At the upper end of the arm is provided a portion in the form of a clasp 3, which joins and laps partially around the main milk tube. This is to obviate a fixed joint. The clasp-end 4 is pierced and formed with a thread, with which the arm-end 6 fits, the thread being so adjusted that it permits movement sufficient to enable the working of the arm to the right or the left. The clasp 3 is cast preferably in brass or white metal. At its shorter terminal 7 it has a small barrel shaped part 8, carrying a lateral pin 9, whose ends project beyond the barrel. The other terminal 12 is curved slightly back upon itself so that it forms a catch. After the clasp has been placed around the main milk tube over a suitable aperture a wire clip 14, is applied, the bow of which engages the turned back catch 12 and the two

hook ends 15, engage the terminals of the pin 9, thus securing a firm attachment and connection between the arm and the main milk tube.

- 5 As the arm is formed of several lengths of tube 17, 18, 19, 20, 21, 22, 23, pierced jointings have been devised to provide for the necessary turning and adjustment. The arm is joined to and suspended from the 10 milk tube in the manner described above. A little below the attachment to the milk tube is the first pierced disk joint 24 and lower down the second disk joint 25 joins to the second length of arm tube. Then 15 there is a third disk joint 26 and a sight-glass 36, then the fourth disk joint 27 and attached thereto a short length of tube, 22, 23, leading to the claw. All the tube referred to is either solid or sometimes spiral 20 metal tube (such as brass or white metal) may be employed.

The construction of the pierced disk joint is illustrated in Figs. 8, 9 and 10. It consists mainly of a pair of disks 28, 29. One 25 of these is soldered across near the end of one length 30 of the tube, the ends of which are closed, a hole 31 being bored in the tube to correspond with the hole in the center of the disk. Around this hole in the disk is a 30 small cylinder or sleeve 32 projecting. The other disk is similarly fitted (but without the sleeve) to the lower piece of tube bored as before-described. The second disk is perforated with a hole adapted to receive the 35 said cylinder or sleeve. A small ring of elastic material 33 is placed within a recess 34 between the two disks, or the disks are ground and fitted closely so as to be milk and air proof. The two disks are held together by means of a suitable spring clip 35 having its ends engaging seats in the walls of the tubes. Sometimes the disk and tube are cast in one piece.

The sight-glass 36 which is fitted to the 45 arm consists of a piece of glass tube fitted at each end into collars 37, 38, connected to the ends of the metal tubes. The said collars are secured together by two wire bolts 39, 40 with nuts 41, 42 as shown in the 50 drawings.

The clasp used to join the subsidiary air tube to the main air tube is illustrated in Figs. 6 and 7. The end of the subsidiary tube 58 is screwed at 44 and on to it fits the 55 tapped end 43 of the ring arm clasp. This is furnished with an india rubber lining 45 whose interior is large enough to slip over the air tube 46. A hole 47 is pierced through the air tube at the desired point 60 and the connection tightened by a wedge 48 or other suitable means.

The last length of metal tube 23 connects with the claw 49 which holds the teat cup. Between the last disk joint 27 and the claw 65 a lateral movement is provided for. The

tube is in two parts 22, 23 each provided with collars 50, 51, and a rubber washer 52 between. One end 23 has a screw fitting into a threaded part on the other end 22 and both screw parts are adjusted to each other 70 so as to allow the claw to move to one side or the other to meet variations in the cow's udder.

The claw part is illustrated in Figs. 12 and 13. An air chamber 53 is provided into 75 which the four air tubes 54, 55, 56, 57, are screwed and a pipe 58 connects with the exhaust. Under the air chamber is another chamber 59 for the milk into which the four 80 milk tubes 60, 61, 62, 63, are screwed. All the milk tubes have taps as usual. The milk chamber is joined on to the end of the arm tube with a tap 64 for opening and closing connection. The tubes between the teat cup 85 and the claw are all made of spiral metal tubing. These and the other spiral metal tubes referred to are constructed of spirally wound strips of metal with a very fine thread of elastic material therebetween. The jointings of the tubes to the teat cups 90 and to the claw are effected in the ordinary way by union couplings.

The present invention provides a more effective draw down motion in combination with the squeezing motion than has ever 95 been attained by machines heretofore in use. To insure engagement of the teat well toward the base there is provided at the crown of the inner inflatable lining 65 (sometimes termed the lining) a rim or 100 fold 66 folding to the outside but with shoulder projecting inward and the edge terminating in a flange 67 adapted to engage a groove 73 specially provided in the outer casing. The drawings show in Fig. 15, a sectional elevation of the teat cup and lining. In Fig. 16 is a sectional plan taken at the line A—A, in Fig. 17 is a sectional plan taken at the line B—B, in Fig. 18 is 105 a sectional plan taken at the line C—C, and in Fig. 19 is a sectional plan taken at the line D—D.

The inner surface of the lining is thickened as shown in Figs. 16 to 19. The wall of the lining thickens taperlike from the upper 115 to the lower portion, being shaped as shown in the drawings. At the point 69 the rigid portion ceases, and from there to the bottom 70 the lining is formed of the bulb shape shown in the drawing which causes it to act 120 like a hinge. At the bottom 70 and at the top 71, the lining is securely fixed to the case. At the bottom this is effected by a capped nipple 72. At the top the fixture is obtained by the rubber flange 67 which fits 125 into the annular groove 73 and is securely held thereby. The air tubes 54—57 are connected with the upper part of the teat-cups and the milk tubes with the bottoms of said teat cups, as shown in Fig. 1. In operation 130

the lining by the pulsatory action of the vacuum and the air pressure is forced inward at 74 the said forces also operating progressively down toward the point of the teat. At the same time the action of the vacuum and atmosphere causes the whole lining to be drawn down till the upper portion 75 of the bulb comes in contact with the lower portion 76. The air chamber 68 being 10 then exhausted the lining releases its grip of the teat and resumes its normal shape and condition ready to repeat the action and so on.

The result of the aforesaid formation and 15 arrangement is to provide for an improved downward motion in addition to the usual squeezing motion, the downward motion being resultant from the described formation of the lining whereby the upper annular extremity is secured to the outer case, but so constructed that the fold part rolls or folds over itself. The central body is rigid as far as downward motion is concerned and moves bodily while the lower annular portion 20 is in the form of a hinge so that these three factors provide or permit a very advantageous downward drawing motion to be obtained, the main central body of the lining 25 acting rigidly and approximating very closely to the action of hand milking or the calf sucking with the correspondingly advantageous results.

The pulsator is a small oblong double-chambered metal box 77 positioned and fixed 30 upon the air pipes 46, the ends of the air pipes being screwed into the two tapped holes 78, 79, of the pulsator, whose ends are specially thickened for that purpose. In the top of the respective chambers 80, 81, are 35 two holes 82, 83, the hole 82 admitting atmospheric air to the air tube. A dome-shaped lid 84 covers and slides upon the top of the box. The function of the two chambers 80, 81 of the pulsator and the two air 40 pipes 46 is to enable a single pulsator to milk the set, one, two or more cows being milked in bails on either side of the pulsator. When the dome 84 is over one port it is causing a vacuum in the teat cups on 45 that side of the pulsator and when over the other port a vacuum in the teat cups on such other side of the pulsator, thereby causing an intermittent air pressure on either side of the pulsator. Flexible pieces of metal 50 tube 85^a 86^a are secured to nipples 85, 86 of the lid 84 and have their other ends connected with the source of exhaust. In the drawing only one of the metal tubes 85^a is shown connected with the exhaust. The lid 55 of the pulsator is actuated by a wire 87 connecting with a portion of the receiver mechanism as hereinafter described.

In connection with and in order to assist in the advantageous working of the foregoing I have devised a special receiving ves-

sel 88. This receiver is connected at 89 to the main milk tube and at 90 to the vacuum tank 91. A door 92 is provided at the top for the purpose of cleaning. Across the bottom and joined thereto is a piece of white 70 or other metal tubing 93. In the top of this tube is an aperture or port 94 and a corresponding one 95 on the opposite side, being inlet and outlet respectively. Fitting telescopically within this tube is another 75 tube 96 one end of which is open, the other end being closed and fastened to a pinion wheel 97. On the side of this inner tube is an aperture 98 of the same length as the others, but of such width that both the other 80 apertures may be closed at the same time. When the pinion is revolved and revolves the inner tube the aperture therein will open the top port only while the other one remains closed, the milk flows into the inner tube and 85 when that rotates and closes the top port, opening the bottom port, the milk is discharged at the bottom port referred to.

In addition to the arrangement shown in Fig. 11 other devices may be employed 90 whereby a connection is effected between the port 94 and the tube 96 or between the port 94 and the port 95.

The pinion before referred to is set in motion by a smaller pinion 99 gearing into it. 95 The smaller pinion has a cone 100 operated from the vacuum pump, for regulating speed. Upon it there is a crank pin 101 having a slotted head 102 to which is secured a rod 102^a, having its other end connected with toggle lever 103 converting the rotary into horizontal motion and actuating wire 87 thus moving the lids of the pulsator backward and forward for the purpose described.

A float valve 104 is provided in the receiver at the outlet to the vacuum tube 90 to guard against the overflow of milk into the said vacuum tube.

In some cases when desired instead of the 110 jointed metal tubing used as described for the milk arm spiral metallic tubing may be substituted. Different forms of the power, the vacuum pump, the receiver and gear wheels, other than as described may be employed.

In operation the power (of whatever nature) is started and begins working the vacuum pump which draws air out of the vacuum tank and in readiness for the cups 120 to be placed on the cows. The belt gearing from the vacuum pump to the receiver cone is placed in position and thus works the cone. The slotted crank arm upon the receiver cone connects with and operates the 125 pulsator rod. Immediately that the cups are placed on the cow, the vacuum is produced inside the lining of the teat cup which in combination with the pressure of atmospheric air from the pulsating air chamber 130

has the effect of causing the milk to flow down through the small tubes and the claw into the milk arm tube and thence upward into the main vacuum tube which also is the main milk tube. The draw caused by the vacuum is constant while the operation of the atmospheric air through the tube provided for that purpose is of a pulsating kind and this has the effect of imparting successive pulsations to the flexible lining formed and arranged as described, the pressure beginning at the top and progressing downward to the point of the teat. The pulsatory action as described is obtained by or through the reciprocating movement of the pulsator. When the valve lid of the same is over the right hand port the power of the vacuum becomes applied and when the lid is over the left hand port the atmospheric air enters the air tube thus producing in the teat cup the pulsatory action referred to.

I claim—

1. A mechanical milker, comprising a teat manipulating mechanism, a main milk tube, an arm of metallic tubing extending from the main milk tube to the teat manipulating mechanism, a swivel joint in the same adapted to enable the teat manipulating mechanism to adapt itself to the physical irregularity of the different cows, a number of swivel joints adapted to enable the metallic tube arm to be adjusted up and down and sidewise, an air tube connected with the teat manipulating mechanism, a pulsator connected with the air tube, a receiver connected with the main milk tube, a discharge device for the receiver, means for operating the pulsator from the discharge device and a vacuum receptacle connected with the receiver.

2. In a mechanical milker, the combination with the milk tube and the claw, of a clasp engaging the milk tube, and an arm having one end secured to the claw and the other end adjustably secured to the clasp, said arm comprising metallic tubing having swiveled joints.

3. In a mechanical milker, an arm adapted to extend from the main milk tube to the claw of the machine and formed of metallic tubing having one or more swiveled joints, each comprising two pierced disks mounted to turn rotatively one to the other and a spring clip for holding the disks together, as and for the purpose set forth.

4. In a mechanical milker, an arm formed of metallic tubing, extending from the main milk tube to the claw of the machine, and comprising a swiveled joint in the arm and having parts connected with each other by a threaded engagement so as to allow the claw to adjust itself as required to the physical irregularity of different cows.

5. In a mechanical milker, a milk tube, an arm formed of metallic tubing extending

from the milk tube to the claw of the machine and having suitable joints adapted to enable the said claw to be moved to right and left and up and down, in combination with a claw comprising an air chamber and a milk chamber into which the air and the milk respectively are led, as and for the purpose set forth.

6. In a mechanical milker, an arm formed of metallic tubing extending from the main milk tube to the claw of the machine and having swiveled joints adapted to enable the said claw to be moved to right and left and up and down, a claw comprising an air chamber and a milk chamber, and air and milk pipes formed of metallic tubing and connected with the air chamber and the milk chamber respectively of the claw.

7. In a mechanical milker, a teat cup comprising a casing, and a lining therefor, said lining having a bulb-shaped lower end reduced in thickness and connected with the casing, whereby it is permitted to move downwardly in said casing.

8. In a milking machine, a teat cup, comprising a casing, and a tapering lining having two of its sides reduced in thickness, said lining having its ends reduced in thickness and connected at its ends with the casing.

9. In a mechanical milker, a teat cup, comprising a casing, and a tapering lining having two of its sides reduced in thickness, said lining having at its upper end a fold whose terminal is in locking engagement with the casing and provided at its lower end with a portion reduced in thickness and secured to the bottom of the casing.

10. In a mechanical milker, a teat cup, comprising a casing having a bottom formed with an aperture therethrough, an outwardly projecting flange located toward the upper edge of said casing, said flange providing an outer annular groove, a flexible lining having at its upper end an outwardly extending fold which terminates in a flange of increased thickness adapted to engage within said annular outer groove in the casing, and having at its lower end a bulb portion with an aperture through the bottom thereof, a nipple extending through the apertures in the bottom of the casing and of the lining and having a flange on its upper end, and means for rigidly securing said nipple to said casing bottom, substantially as described.

11. In a mechanical milker, a teat cup, comprising a casing having an annular groove at its upper end, and a tapering lining having two of its sides reduced in thickness, said lining having at its upper end an outwardly extending fold terminating in a flange engaging the groove of the casing, the lower end of the lining being reduced in thickness and approximately bulb-

shape and secured to the bottom of the casing.

12. In a mechanical milker, a teat manipulating mechanism, an air tube connected with the teat manipulating mechanism, a milk receiver, a discharge device for the receiver, a pulsator connected with the air tube, and means for operating the pulsator from the discharge device of the receiver.

10 13. In a mechanical milker the combination of a milk receiver, a discharge device for the receiver, a pulsator, and means for operating the pulsator and the discharge device of the receiver conjointly, substantially as described.

14. In a milking machine, a teat cup comprising a case having a lining therein, whose walls vary in thickness progressively from the top to the bottom thereof, said lining being thicker in cross section at the bottom than at the top thereof, said lining having a relatively thin extension projecting from the top and bottom and having each free end fastened to said case, the upper extension folded inward to form a teat gripping shoulder, and a vacuum forming means con-

nected to said case adapted to pulsate said lining.

15. A mechanical milker comprising a teat cup, a suction pipe connected with the said cup, a pulsator arranged in the suction pipe, a milk tube connected with the teat cup, a vacuum tank, a receiver connected with the milk tube and vacuum tank and having a discharge valve in its bottom, and means for simultaneously operating the valve of the receiver and the pulsator.

16. In a mechanical milker, a teat manipulating means, an air tube connected with the teat manipulating means, a pulsator with which the air tube is connected, a milk receiver, a rotary discharge valve at the bottom of the receiver, means for operating the valve, and means for operating the pulsator from the valve operating means. 45

Signed at Melbourne this twenty-second day of August, A. D. 1911.
